UNITED STATES PATENT OFFICE.

HARRY DANIEL MOSAUER, OF NEW YORK, N. Y., ASSIGNOR TO TUSKELOID COMPANY, INC., OF NEW YORK, N. Y., A CORPORATION OF NEW YORK.

DESIGN FOR A HANDLE FOR TOILET ARTICLES.

58,679.

Specification for Design.

Patented Aug. 9, 1921.

Application filed November 29, 1920. Serial No. 427,236. Term of patent 7 years.

To all whom it may concern:

Be it known that I, HARRY D. MOSAUER, a citizen of the United States, residing at New York, in the county of New York and State of New York, have invented a new, original, and ornamental Design for a Handle for Toilet Articles, as shown in the accompanying drawing and described in the following specification.

Figure 1 is a face view of a handle, an article of manufacture, embodying my design.

Fig. 2 is an edge view of the same.

I claim:

The ornamental design for a handle for toilet articles as shown.

HARRY DANIEL MOSAUER.
